THERMOSTATIC SWITCH

Benjamin E. Getchell, Plainville, Conn., assignor
to The Trumbull Electric Manufacturing Company, Plainville, Conn., a corporation of Connecticut

Application April 10, 1943, Serial No. 482,559

7 Claims. (Cl. 200—138)

1

My invention relates to snap action switches actuated by bimetallic members.

The main object is to eliminate the need for grinding and sharpening pivot points of the thermostatic switch.

Another object is to provide a simple reliable device which can be commercially made and readily adjusted.

Another object is to provide a thermostatic switch which can be adjusted without distorting the bimetal member.

Another object is to provide a device which does not readily get out of adjustment.

Another object is to provide a device, the parts of which can be economically made and assembled.

Fig. 1 is a plan view of a switch embodying one form of my invention.

Fig. 2 is an edge view of the same.

Fig. 3 is a rear view of the same.

Fig. 4 is a plan view of the blank from which the base is formed on a reduced scale.

Fig. 5 shows a plan and edge view of the contact trip member.

Fig. 6 shows a plan and edge view of the support for the contact trip.

Fig. 7 is an enlarged detail view showing the means for supporting the contact trip member.

The base 7 is of sheet metal, for instance steel. The switch contacts 8, 9 are carried by one end of the base but suitably insulated from it for instance by fibre washers 10, 11. The stationary contact 8 has a soldering lug 12. The support 13 is preferably of phosphor bronze and riveted to the base but insulated from it and provided with a wire terminal 14 at the back. It may have a small boss 13' projecting into the insulation 11 so as to hold the support in proper alignment, the metal base being cut away as at 7' to avoid contact between the metal parts.

The trip member 15 which carries the movable contact 9 is preferably of hard brass and hinged to the support 13. A knife edge hinge bearing is effected in a very simple manner. The support 13 has two upstanding posts 14' formed with bent angle recesses 16 of slightly over 90° angle to receive the sharp cut edges 17 formed in blanking the trip member from sheet metal and which constitute the pivot or hinge of the trip member 15. The lugs 18 of the trip member beyond the knife edges extend past the posts 14' so as to prevent sidewise displacement. The tail piece 19 extends from the trip member in the direction opposite to the contact 9 and serves partially to counterbalance the trip member and also to act

as a stop to limit the opening action by striking against the upturned edge 20 of the support. It will thus be seen that the trip member is supported by the very member which acts as an abutment for its open circuit action. This prevents the stop from changing even if the main base or the insulating washer should be displaced or warp.

The bimetallic arm 21 has one end riveted to the lug 22 which is formed as an integral part of the base 7 and offset from the end 23 which is bent back over the adjacent top of the base. The other end of the arm 21 is connected by a snap action spring 24 to the trip member 15 between the contact 9 and the hinge line. The bimetallic arm can be so adjusted as to normally hold the circuit closed or open. Preferably an insulating piece 25 is interposed between the arm and the spring.

Adjustment of the bimetallic arm can be readily effected by tightening or loosening the screw 26 which is screwed into the base and engages the underside of the end 23 to bend the end more or less. It will be seen that such adjustment does not bend or distort the arm 21 at all but does change its position by reason of the movement of the lug 22 with the end 23. The end is sufficiently resilient to automatically return to its former position when released by retraction of the screw.

The type of knife edge support of the movable trip member is very simple and easy to make as it does not require grinding or fitting of pivot pins or bearings. By bending a part of the blank of the contact trip member 15 at an angle of 45° to its main axis, the corner of the cut edge 17 formed in blanking the piece from sheet metal serves as a sharp edge similar to a knife edge. The angle 16 formed by stamping the post is made slightly greater than 90° and serves as a stationary bearing for this knife-like edge 17.

It will be noted that the thermostatic member in this switch is simply a straight strip—all adjustment is effected by movement of a part of the base. This adjustment can easily cover a range of operation of the thermostat from below 0 degrees to about 300 degrees F.

The differential between the "off" and "on" positions of the trip member 15 can be adjusted by bending the tail piece 19 to increase or decrease the break distance between the contacts 8 and 9.

I claim:

1. A thermostatic switch comprising a base, a trip contact member hinged at one end of the

base, the opposite end of the base having a return bend with an offset lug cut from an intermediate part of the base and extending away from the contact end, a bimetal arm secured to said lug and connected to said trip contact member and an adjusting screw in the base adapted to engage and move the return bend and lug of the base for varying the action of the bimetal arm.

2. A snap switch having a sheet metal support with a supporting post bent to form two flat angular portions providing an open angle recess slightly over 90°, a movable contact carrying member blanked from sheet metal and bent so as to present a right-angled corner of a cut edge into the angle recess, the corner of this cut edge thereby forming a sharp edge pivot for the movable contact member.

3. A snap switch having a sheet metal support with a supporting post bent to form two flat angular portions providing an open angular recess slightly over 90°, a movable contact carrying member blanked from sheet metal and formed with a cut edge sheared at right angles to the adjacent surface and bent so as to present a right-angled corner of said cut edge into the angular recess, said corner forming a sharp edge pivot for the movable contact member and spring means for normally holding the corner of the edge against the corner of the angular recess.

4. A thermostatic switch comprising a base member having a flat body portion with one end thereof bent backwardly upon but spaced from the body portion, an integral lug portion carried by said bent portion, a stationary contact carried by said base, a movable contact, a bimetal arm having one end fastened to said lug portion and its other end connected to said movable contact for actuating the same and means for adjusting the position of said arm including a screw member carried by and movable through said base into the space between said bent portion and the base and directly engaging said bent portion for adjusting the relative position of the arm and base.

5. For use in an electric switch having a sta- 45

tionary support formed with angularly disposed flat portions providing an open angle recess at least slightly over 90° and of substantial length, a movable member having its body blanked from sheet metal, said body having end portions disposed in the same plane, one of said end portions carrying a contact member and the other end portion acting as a stop and counterbalancing member, the portion of said body between said end portions being bent out of the plane of said end portions and being provided with an elongated edge portion cut at right angles to the plane of the adjacent portion thereby forming right angled corners, said member and support being so positioned relatively that a sharp corner of said cut edge portion provides a knife-edged pivot for the movable member in the open angle recess of the support.

6. In an electric switch, a stationary member 20 formed of sheet metal with an elongated open angle recess in one surface formed by bending one portion with respect to the adjacent portion, the walls of said recess extending at an angle of more than 90° with respect to each other, a movable member pivoted in said recess, said movable member being blanked from sheet metal and having an elongated edge cut at substantially right angles to the adjacent metal so as to provide a sharp corner at one surface, said corner being seated in said recess and serving to support said movable member in the manner of a knife edge.

7. A thermostatic switch having a sheet metal support with two upstanding integral posts bent 35 to form angular recesses, a sheet metal trip contact member having spaced-apart cut edges forming knife edges seated in said recesses, said edges being formed by shearing the metal at right angles to the main surface and a bimetal arm 40 having one end stationary and a spring extending between the posts and connecting the other end of the bimetal arm to the trip member and holding the cut edges in the recesses.

BENJAMIN E. GETCHELL.
